COMBINATION FOUNTAIN FEEDER AND
WATERER

Clarence G. Muehlfeld, Bridgeport, Mich.

Application March 14, 1951, Serial No. 14,483

Term of patent 14 years

(Cl. D12—2)

To all whom it may concern:

Be it known that I, Clarence G. Muehlfeld, a citizen of the United States of America, and a resident of Bridgeport, in the county of Saginaw and State of Michigan, have invented a new, original, and ornamental Design for a Combination Fountain Feeder and Waterer, of which the following is a specification, reference being had to the accompanying drawing, forming part thereof.

In the drawing:

Fig. 1 is a perspective view of a combination fountain feeder and waterer with the cover in closed position, showing my new design.

Fig. 2 is a view similar to Fig. 1 showing the cover in raised position.

Fig. 3 is a side elevational view.

Fig. 4 is a top plan view.

I claim:

The ornamental design for a combination fountain feeder and waterer, as shown.

CLARENCE G. MUEHLFELD.
